UNITED STATES PATENT OFFICE.

ARTHUR M. CRICHTON, OF UNIONTOWN, PENNSYLVANIA, ASSIGNOR TO MEASURED SERVICE METER COMPANY, A CORPORATION OF DELAWARE.

MEASURED-SERVICE TELEPHONE.

Application filed October 16, 1920. Serial No 417,398.

To all whom it may concern:

Be it known that I, ARTHUR M. CRICHTON, a citizen of the United States, and a resident of Uniontown, in the county of Fayette and State of Pennsylvania, have made a new and useful Invention in a Measured-Service Telephone, of which the following is a specification.

My invention relates to telephone exchange systems and the object thereof is to provide a timing device in connection with such a system which depends for its operation upon the closure of a subscriber's hook switch and is automatically effective after a predetermined period to interrupt the talking connection. A further object of my invention is to provide a timing device in connection with a telephone system which automatically signals the operator after the expiration of a predetermined interval after the establishment of a telephonic connection. A still further object of my invention is the provision of a timing device in connection with a telephone circuit which is effective after the expiration of predetermined period to interrupt telephonic communication and which may be reset by the operator prior to the arrival of the period of interruption so that the subscriber may talk for a further period or periods.

In the drawings, Figure 1 is a front elevation of the timing device showing the contact control element in the zero position; Figure 2 is a view similar to Figure 1 but showing the contact operator in a different position; Figure 3 is a side elevation of the timing device; Figure 4 is a bottom plan view; Figure 5 is a detailed view showing the spring for normally biasing the ratchet cam to a zero position; Figure 6 is a detail view of one of the contacts; and Figure 7 is a view showing the circuit connections.

My present invention relates to a timing device whereby, after the establishment of a telephonic communication between subscribers, the timing device begins to act and continues to operate for a desired interval of time, whereupon the central operator is notified of the approach of the expiration of the period and may then notify the calling subscriber that the call period is about to expire and that if he desires to continue conversation to deposit more toll or record another call after which the timing device is reset to a zero position.

In accordance with my invention, if the operator should fail to notify the subscriber that the conversation period is about to expire, or should the subscriber disregard the warning, the timing device automatically effects an interruption in the talking circuit at the completion of the predetermined period. Although I have shown my invention related to a telephone meter device such as set forth in my co-pending application, Serial No. 373,674 filed April 13, 1920, it will be obvious that the timing device herein described might be used in connection with any system for limited telephone service, such, for instance, as pay stations, or stations having limited numbers of calls.

Having briefly set forth the objects of my invention and the situations in which it may be used, I will now refer more particularly to the details of construction involved. Briefly, my construction comprises a motor-operated interrupting device for interrupting telephonic communication after a predetermined time and is provided with controlling circuits, one a holding circuit and the other an actuating circuit more particularly hereinafter referred to. The motor device, as shown in Figure 1, is enclosed within a suitable casing 9 and it is arranged to be situated in any convenient or desirable place in a telephone exchange. The device includes a face plate 10, preferably made of non-magnetic material and supporting at the sides thereof a signaling contact 11 and an interrupting contact 12. The contact 11 comprises two leaf spring contact elements 13 and 14 separated from each other and from the face plate by any suitable insulating material, and the contact 12 comprises two leaf spring contact elements 15 and 16 separated from each other and from the face plate by insulating material.

The face plate 10 supports a rotatable ratchet wheel 17 having ratchet teeth 18. Between the face plate and the back of the ratchet wheel there is connected a spiral spring 19, (see Fig. 5), one end of the spring being attached to the face plate 10 and the other end being attached to the ratchet wheel 17 for normally biasing the latter to its zero or normal position. A stop, comprising abutments 20 and 21, carried preferably by the wheel and face plate, determine the normal or zero position, the spring being under tension at such position. The front face of

the ratchet wheel is provided with two cam faces 22 and 23 at different radial distances from the center for cooperating with the contacts 11 and 12 aforesaid.

5 The face plate and the other parts heretofore set forth are supported or connected to a frame member 24, and the latter element supports two electro-magnets 25 and 26, the magnetic paths therefor being completed by 10 the supporting connection at the upper end. At the lower ends of the electro-magnets, there is arranged an armature supporting element 27, preferably made of non-magnetic material; and openings 28 and 29 are 15 provided therein for the cores 28' and 29' of the electro-magnets 25 and 26, respectively, whereby the magnetic flux may act on the armature elements 30 and 31 hinged to the supporting element and draw said armature 20 elements toward the electro-magnets upon energization of the latter.

10 The ratchet wheel 17 is moved forward step-by-step by means of an actuating pawl comprising a pawl portion 32 which is 15 biased and hinged to engage the ratchet wheel, the pawl portion being hinged at 33 to the upper end of a reciprocatory post 34, the latter being normally maintained in a 20 position to disengage the pawl portion from the ratchet wheel by means of a spring 35 engaged between an upper lug 36 carried by the face plate 10 and constituting a guide for the post and an enlarged portion 37 carried by the post. The pawl portion is 25 normally moved toward the ratchet wheel by a spring 38. The face plate is provided with a 30 additional lug 39 having an opening of the same shape as the enlargement 37 and constituting a lower guide for the post. The armature 30, actuated by means of the electro-magnet 25, cooperates with the lower 35 end of the post 34 to move the latter upward in order to advance the ratchet wheel 17.

15 A holding pawl or detent 40 is provided for the ratchet wheel and it is made in two parts 41 and 42 hinged together, the part 41 being the nose or pawl portion. A leaf spring 43 is secured to the part 42 and cooperates with the nose portion 41 to secure a 20 yielding engagement of the latter with the ratchet wheel. The detent or pawl portion 42 is provided with a lug or projection 44 designed to cooperate with the other armature element 31 which is responsive to the 25 electro-magnet 26 in order to bring the holding pawl or detent 40 into engagement with the ratchet wheel 17 to prevent retrograde movement of the latter.

30 Means are provided for limiting adjustably the range of movement of each of the armature elements. The armature element 30 is provided with an aperture through which extends a threaded post 45 and a nut 46 is threaded to the post below the armature element whereby the range of move-

ment of the latter may be adjusted. A similarly arranged nut 46' cooperates with the other armature element 31 for a like purpose.

5 My motor device then includes two important movable elements, one a holding pawl for the ratchet wheel, and the other an actuating pawl. The holding pawl is 10 designed to be engaged with the ratchet wheel as soon as the operator plugs in the called subscriber's jack. Connections are established 15 for the magnet of the actuating pawl by closure of the called subscriber's hook switch, the connections including a clock-operated make-and-break contact whereby timed 20 impulses are sent through the magnet 25 in order that the latter may be energized intermittently and actuate the pawl associated therewith in the like manner to cause a 25 step-by-step movement of the ratchet wheel. 30 As herein set forth, the ratchet wheel 17 is provided with two cam portions 22 and 23, one designed to close a contact 11 near the end of the talking period so as to signal 35 the exchange operator and the other designed to open the contact 12 a short interval after the closure of contact 11 to interrupt the talking circuit.

40 Having set forth in more or less detail the structure involved in the timing device, I will now describe more fully the connections and controlling circuits thereof. Upon reference to Figure 7, it will be seen that the left hand portion thereof constitutes a diagrammatic showing of a station 45 equipped with my telephone meter device disclosed in my co-pending application aforesaid and which does not constitute a part of this invention but is shown merely for the purpose of indicating the desirable 50 association thereof with the present invention. The right hand portion of Figure 7 indicates a cord and plug connection for the purpose of connection with the jack 50 of a calling subscriber and with the jack 51 of 55 a called subscriber. The connection comprises condenser circuits which are old and well known in the art, said circuits terminating in the usual rings and tips of calling 60 plugs. Referring to the right hand side of Figure 7, when the operator inserts the calling plug into the jack 51, a local circuit is completed from the battery 52 through the relay winding 1, the wire 53, the ring 65 spring of the jack 51 and then through the winding of a cut-off relay (not shown) to the ground, thereby energizing relay 1 and causing the contact armature element 54 to engage the contact 55, thereby completing 70 a circuit from the battery 56 through the contacts 54 and 55, the wire 57, the contacts 58 and 59, the wire 60, the winding of the holding magnet 26, and to the ground at 61. The motor magnet 25 is energized 75 in the following manner: When the called 80

party answers, the relay 2 is energized due to the passage of current through the lines 62, 63, 64, the contact 65, the line 66, the winding of the relay 2 to the ground. Energization of the relay 2 results in the closure of a circuit for the relay 7, the current passing from the battery 69, through the contacts 68 and 67 the line 70, and the winding of the relay 7 to the ground. Energization 10 of the relay 7 results in movement of the contacts 71 and 72 into contact with the lines 73 and 74, respectively, to complete a circuit from the battery 85 for the motor magnet 25 in the manner more particularly 15 hereinafter pointed out.

With the energization of the relay magnet 3 of the supervisory lamp system, the contact 75 is drawn into contact with the line 74, thereby closing the circuit, including the 20 battery 80, for the energization of the relay 5; current passing from the battery 80, through the winding of the relay 5, the line 77, the contact 78, the line 76, the contact 75, the line 74, the contact 72, which is 25 closed by said relay 7, the lines 83 and 84, and the contact 84' to the ground, the latter contact being closed due to energization of the relay 1, already referred to.

Energization of the relay 5 results in 30 the closure of a circuit for the relay 6 by drawing the contact 81 into contact with the wire 82, said circuit including the battery 85, the line 86, the winding of the relay 6, the line 82 and the contact 81 to the ground.

Energization of the relay 6 results in closure of the contact 87 with the line 89 so that current may pass from the battery 85, through the lines 88 and 89 and through 40 the contact 71, which has been moved into contact with the line 73 due to the energization of the relay 7, the line 73, the winding of the actuating or motor magnet 25, the line 90, and the clock 91 to the ground 45 at 61. The clock 91 is arranged in the central office and may be of any well known type designed to provide impulses of a fair degree of frequency. The clock is provided with a make-and-break contact device where- 50 by the winding of the motor magnet 25 is subjected to intermittent actuating impulses responsive to the making and breaking of the contact by the clock. This causes the actuating pawl to be moved in a step-by-step manner and in synchronism with the clock.

From the structure above set forth it will 60 be seen that the ratchet wheel 17 is held from retrograde movement as soon as the plug is inserted in the called subscriber's jack by means of the holding pawl 40 which is maintained in engagement therewith by the holding magnet 26. Current from the 65 battery 85 passes through the winding of the motor magnet 25 and the connection there-

from to the ground is made and broken by the clock mechanism 91 thereby energizing the motor magnet with a predetermined timed frequency, whereby the pawl associated therewith imparts to the ratchet 70 wheel a step-by-step movement in synchronism with the clock. It will be obvious that the ratchet wheel may be caused to operate through any desired arc within 75 limits before means are actuated to signal the operator or interrupt the talking circuit. In the particular system herein shown, the ratchet wheel is provided with a sufficient number of teeth so that when it is actuated for a distance of nearly 360°, 80 a period of five minutes will have elapsed; however, it is obvious that the duration of operation is determined by the time of a standard call.

The face of the ratchet wheel is provided with a cam element 22 which is arranged to cooperate with the contact 11, to engage the contact elements 13 and 14 near the end of the period of movement of the ratchet wheel 17, or near the end of the 90 determined period of the conversation. Upon closure of the contacts 13 and 14 current flows from the battery 95 through the lamp 96, wire 97, contacts 13 and 14, to the ground at 61, thereby notifying the exchange operator that the conversation period is about to expire. The operator thereupon notifies the calling subscriber that the period is about to expire and that if it is desired to 95 continue the conversation, the subscriber should deposit more toll or register another call. If it is desired to continue the conversation through a further period, the operator presses the key 58 which breaks contact at 59, thereby breaking the circuit for 100 the holding magnet 26, whereupon the spring 40' for the holding pawl forces the latter out of engagement with the ratchet wheel 17 and the spring 19 connected between the face plate 10 and the ratchet wheel 110 17 acts on the latter and causes it to move back to zero or starting position, and as soon as the operator allows the key 58 to go back into engagement with the contact 59, the circuit through the holding magnet 115 is again completed and the holding pawl is brought back into engagement with the ratchet wheel, the motor magnet 25 operating all the while, and as soon as the holding pawl is re-engaged with the ratchet wheel, the latter is caused to move forward in a step-by-step manner by means of the pawl actuated by the motor magnet for a further period.

Should the operator fail to note the signal that the period of conversation is about to expire, or should the subscriber fail to pay any heed to a warning to that effect, the other cam 23 on the ratchet wheel 17 125 operatively engages an insulated interrupt- 130

ing member 23' passing through an appropriate opening in the contact spring 15 to engage the contact spring 16 for lifting the latter away from the spring 15, thereby 5 breaking a talking circuit through the spring elements 15 and 16. See Fig. 6.

When the conversation is finished, the operator removes the calling plug from the jack, whereupon the relay 1 is de-energized 10 and the contact 54 is broken, thereby stopping the flow of current from the battery 56 to the holding magnet 26, allowing the holding pawl 40 to be moved back to a disengaged position under the influence of 15 spring 40'. As soon as the holding pawl is disengaged from the ratchet wheel, the spring associated with the latter brings it back to its initial or zero position.

Briefly, apparatus in accordance with my 20 invention operates as follows: A calling subscriber removes his receiver whereupon the line lamp in the central station is illuminated in the usual way, whereupon the operator inserts an answering plug and ascertains 25 from the subscriber the number desired. As soon as the answering plug is inserted, the relay 3 is energized, the operator then inserts the calling plug of the connecting cord into the jack of the called 30 subscriber, whereupon a circuit is immediately established for the holding magnet of the intermittently actuated motor for interrupting the talking circuit. As soon as the called subscriber removes his receiver, the hook switch is closed and a circuit is established 35 for the winding of the motor magnet 25, which circuit is interrupted by means of the central clock as hereinbefore referred to. The ratchet wheel of the motor device 40 operates for a predetermined period whereupon the cam 22 closes the contacts 13 and 14 of the lamp 96, thereby completing a circuit for the latter and permitting it to become 45 illuminated. Shortly after the lamp circuit is made, the other cam 23 on the face of the ratchet wheel comes into engagement with an insulated interrupter element 23' which serves to disengage the contacts 15 and 16, thereby interrupting the talking 50 circuit. As hereinbefore set forth, the operator may inform the subscriber that his conversation period is about to expire and may disengage the holding pawl by moving the key 58 out of engagement with the contact 59, thereby breaking the circuit for the holding magnet 26, whereupon the holding pawl is moved out of engagement with the ratchet wheel and the spring behind the latter immediately pulls it back to zero 55 or initial position, thereby avoiding interruption of the talking circuit and permitting 60 conversation for a further period.

While I have shown my invention in but one form, it will be obvious to those skilled 65 in the art that it is not so limited, but is

susceptible to various other changes and modifications, without departing from the spirit thereof, and I desire, therefore, that only such limitations shall be placed thereupon as are imposed by the prior art or as 70 are specifically set forth in the appended claims.

What I claim is:—

1. In a telephone exchange system, the combination of a calling subscriber's line, 75 a called subscriber's line, connecting means for establishing communication between the lines, an interrupting device for the connecting means, and timing means cooperating with the interrupting device and rendered operative by the called subscriber to secure interruption of communication after the lapse of a predetermined interval.

2. In a telephone exchange system, the combination of a calling subscriber's line, a called subscriber's line, connecting means for establishing communication between the lines, an interrupting device for the connecting means, timing means for operating said device after a predetermined period, and means to initiate movement of said timing means upon the hook switch of the called subscriber being closed. 85

3. In a telephone exchange system, a connecting unit for establishing communication 95 between calling and called subscribers, comprising connected lines, an interrupting device in one of the lines, a means creating periodic electric impulses, means operable 100 by said periodic impulses for operating said interrupting device, a circuit between the impulse creating device and the means operated thereby, and means operated by the closure of the called subscriber's hook switch for closing said last named circuit. 105

4. In a telephone exchange system, the combination of calling and called stations, a connecting cord including talking circuit elements, an interrupter for one of the said elements, actuating means to operate the interrupter after a predetermined period of operation, and means to effect movement of the actuating means rendered operative 110 from the called station.

5. In a telephone system, the combination 115 of a connecting cord including talking circuit elements, an interrupting device for one of the said elements including contacts, step-by-step mechanism, cam means carried by the step-by-step mechanism and adapted after a predetermined period of operation of the latter to cooperate with the contacts to effect disengagement of the latter, electro-magnetic means cooperating with the step-by-step mechanism, and a switch which is opened and closed by a called subscriber for controlling the circuit of said electro-magnetic means. 125

6. In a telephone exchange system, the combination of a connecting cord including 130

5 talking circuit elements, an interrupter in one of the said elements, a ratchet wheel, actuating and holding pawls for the ratchet wheel, electro-magnetic means for causing the holding pawl to engage the ratchet wheel responsive to the initial connection of the cord with a called subscriber's line, electro-magnetic means for operating the actuating pawl including a timed make-and-break means and responsive for its operation upon the establishment of communication with the called subscriber, a signal device including a circuit, contacts therefor, normally closed contacts for one of the talking circuit elements, cams carried by the ratchet wheel, one cooperating with the signal contacts to render the signal operative after a predetermined period of operation of the ratchet wheel and the other cooperating 10 with the contacts of the talking circuit element to break the circuit therethrough shortly after the establishment of the signal circuit connection.

15 7. In combination with a telephone exchange system including calling and called subscribers' lines and a connecting means for the latter having talking circuit elements, an interrupting device for one of the talking circuit elements of the connecting means including normally closed contacts, means for disengaging the contacts after a predetermined interval, and means for rendering the disengaging means operative dependent 20 upon closure of the called subscriber's hook switch.

25 8. In combination with a telephone exchange system including calling and called subscribers' lines and connecting means therefor having talking circuit elements, an interrupting device for one of the elements, a motor-device depending for its operation upon the closure of the called subscriber's hook switch, and means carried by the motor-device for disengaging the contacts 30 after a predetermined period of operation of the motor-device.

35 9. In combination with a telephone exchange system including calling and called subscribers' lines and connecting means for the latter having talking circuit elements, an interrupting device for one of the said elements including normally closed contacts, a motor-device for opening the contacts after a predetermined period of operation, means 40 to actuate the motor-device in response to closure of the called subscriber's hook switch, a signal circuit, and means carried by the motor-device to effect closure of the signal circuit before interruption of the talking element contacts.

45 10. In combination with a telephone exchange system including calling and called subscribers' lines and connecting means for the latter having talking circuit elements, an interrupting device for one of the said 50 elements including normally closed contacts, a signal device including a circuit having normally open contacts, a cam wheel having cam portions, one portion arranged to cooperate with the contacts to close the signal contacts before the talking circuit contacts are opened, and the other cam portion arranged to thereafter open the closed contacts, ratchet teeth on the cam wheel, a holding pawl cooperating with the ratchet teeth 55 and normally disengaged therefrom, electro-magnetic means for bringing the holding pawl into engagement with the ratchet teeth responsive to initial engagement of the connecting means with the called subscriber's line, an actuating pawl adapted to engage the ratchet teeth, and electro-magnetic means for giving to the actuating pawl an intermittent movement responsive to the closure of the called subscriber's hook 60 switch.

11. In combination with a telephone exchange including calling and called subscribers' lines and connecting means therefor having talking circuit elements, closed contacts for one of said elements, step-by-step mechanism having an element capable of separating the contacts after a predetermined period of motion, electro-magnetic means for holding the element in position 65 which is dependent upon closure of the called subscriber's hook switch for energization, and manual means for interrupting the circuit of the holding means whereby the element may be allowed to return to initial 70 position.

12. In combination with a telephone exchange system including calling and called subscribers' lines and connecting means therefor having talking circuit elements, normally closed contacts for one of said elements, a signal device, moveable means cooperating with the signal device and contacts to render the signal operative after movement of the moveable means from its initial position for a predetermined period 75 and to open the contacts an interval after the signal is rendered operative, means for causing movement of the moveable means, means opposing movement of the moveable means and tending to return it to initial 80 position, and means under control of the operator for rendering the movement causing means ineffective.

13. In combination with a telephone exchange system including calling and called subscribers' lines and connecting means therefor having talking circuit elements, normally closed contacts for one of the elements, a signal device, a circuit therefor including normally open contacts, a ratchet wheel having cam portions effective in sequence to close the open contacts and open the closed contacts, means to bias the ratchet wheel into a zero or initial position, a hold- 85 90 95 100 105 110 115 120 125 130

- ing pawl, means for biasing the holding pawl out of engagement with the ratchet wheel, electro-magnetic means opposing the biasing means and adapted to maintain the holding pawl in engagement with the ratchet wheel, an actuating pawl, means for biasing the actuating pawl out of engagement with the ratchet wheel, electro-magnetic means for causing the actuating pawl to operatively engage the ratchet wheel, clock mechanism for making and breaking the circuit of the second electro-magnetic means whereby the latter is intermittently energized and the actuating pawl is given an intermittent and reciprocatory movement to intermittently move the ratchet wheel, and means under the control of the operator for breaking the circuit of the first electro-magnetic means whereby the ratchet wheel may be returned to zero or initial position before the closed contacts are opened.
14. In combination with a telephone exchange system including calling and called subscribers' lines and connecting means therefor having talking circuit elements, normally closed contacts for one of the elements, a ratchet wheel having a cam portion to open the closed contacts after movement of the wheel a predetermined degree from its initial or zero position, means to bias the ratchet wheel into a zero or initial position, a holding pawl, means for biasing the holding pawl out of engagement with the ratchet wheel, electro-magnetic means opposing the biasing means and adapted to maintain the holding pawl in engagement with the ratchet wheel, an actuating pawl, means for biasing the actuating pawl out of engagement with the ratchet wheel, electro-magnetic means for causing the actuating pawl to operatively engage the ratchet wheel, and clock mechanism for making and breaking the circuit of the second electro-magnetic means whereby the latter is intermittently energized and the actuating pawl is given an intermittent and reciprocatory movement to intermittently move the ratchet wheel.
15. In a telephone system, the combination of a signal circuit including a signal and contacts, a talking circuit including contacts, a called subscribers' hook switch, mechanism for closing the first contacts and opening the second contacts sequentially, and means rendered effective by closure of said hook switch to secure operation of said mechanism.
16. In a telephone system, the combination of calling, called, and central stations, circuits for connecting the stations, a circuit interrupter at the central station, means under the control of the called station for operating the interrupter, and a signal at the central station which is operated by said means before the interrupter is operated.
17. In a telephone system, the combination of a talking circuit including contacts, a cam for disengaging the contacts, time-controlled mechanism for operating the cam, and means for resetting the cam body to its starting position without interrupting of the talking circuit.
18. In a telephone system, the combination of a talking circuit including contacts, a signal circuit including a signal and contacts, a cam body having a cam portion for closing the latter contacts and a cam portion for opening the first contacts in sequence, and time-controlled mechanism for actuating the cam.
19. In a telephone system, the combination of a talking circuit including contacts, a signal circuit including contacts, a cam body having a cam portion for opening the first contacts and a cam portion for closing the second contacts before the first contacts are opened, time-controlled mechanism for moving the body from a starting position, and means for resetting the cam body to its starting position without interruption of the talking circuit.

In testimony whereof I have hereunto subscribed my name this 16 day of September, 1920.

ARTHUR M. CRICHTON.
